UNITED STATES PATENT OFFICE.

CHARLES VAN DE MARK, OF OAKS CORNERS, NEW YORK.

METHOD OF UNITING THE PANELS OF PORTABLE FENCES.

Specification forming part of Letters Patent No. 17,459, dated June 2, 1857; Reissued July 10, 1860, No. 1,006.

To all whom it may concern:

Be it known that I, CHARLES VAN DE MARK, of Oaks Corners, in the county of Ontario and State of New York, have invented, made, and applied to use a new and useful Improvement in Portable or Field Board Fences; and I do hereby declare that the following is a full, clear, and exact description of the construction and operation 10 of the same, reference being had to the annexed drawing, making part of this specification, wherein—

Figure 1 is a plan of my fence as in place for use and Fig. 2, is a side elevation of the 15 same.

Similar marks of reference denote corresponding parts.

The nature of my said invention consists in constructing panels or trays of boards in 20 such a manner that they shall lock together by means of end pieces, and form, when set in a worm or zig zag shape, a very strong but portable field fence, and one that can be put together with the greatest facility 25 and speed, or removed and packed away into a small compass.

The panels or trays of my fence are formed of uprights or posts *a*, *b*, *c*, and *d*, two or more of which (*a* and *c*) are slightly 30 longer than the others, to rest on the ground.

e, and *f*, are the top and bottom rails of the fence passing from the post *a*, to the locking board *d*.

g, *g*, *g*, are intermediate rails of the desired number for the height of the fence. These intermediate rails *g* do not connect to the end locking board *d*, but pass from the post *c*, to a locking board *h*, which is of a 35 length sufficiently less than the board *d*, to allow the same to be entered through the opening between the posts *c* and *d*, as the panels are being locked together. The posts *a*, and *d*, are on one side of the rails *e*, *f*, *g*, and the posts *b* and *c*, and locking board *h* 40 on the other, and the parts of each panel are to be securely fastened together at the points of intersection.

It will now be apparent that the successive panels or trays of the fence are to be

locked together by inserting the piece *h*, 50 and projecting rails *g* through the opening of the next panel, between the posts *c*, and board *d*, and swinging the panels around until the locking board *h*, comes against the post *c*, and the locking board *d* comes 55 against the post *a*, and forms a worm or zig zag fence, and the locking boards *h* and *d*, drawing tightly against the end posts *c*, and *a*, form a firm and secure fence and one that cannot be removed except by commencing 60 at one end or opening.

I would remark that the panels or trays must be handed, that is to say, the posts *a*, *d*, and *c*, *b*, *h*, alternately on opposite sides so as to allow the fence to be placed in the zig 65 zag position, and the angles of this zig zag may be more or less obtuse according to the stability required of the fence, and said angles are regulated by the distance between the locking boards *d*, *h*, and posts *a*, *c*. 70

At one or several places around a lot it becomes necessary to have entrances or gateways, to provide for which I attach one of the locking boards *d*, by a bolt and nut at one end as at *i*, and attach a hook *k* at the 75 other so that said board can be turned down to allow the piece *h*, to be swung out and effect an opening in the fence. My fence thus becomes adapted to a great many positions and circumstances, and the panels are 80 drawn tightly, and a very firm corner obtained, by simply drawing the angles of the fence into the most obtuse position making the pieces *h* and *d* sit tightly against the posts *a* and *c* and rails *e*, and *f*. 85

What I claim and desire to secure by Letters Patent is—

The end locking piece or board *h*, combined with the locking board *d*, and rails *e*, *f* and *g*, the whole constructed and operating 90 substantially as and for the purposes specified.

In witness whereof I have hereunto set my signature this tenth day of April 1857.

CHARLES VAN DE MARK.
